UNITED STATES PATENT OFFICE.

JOHN HENRY DOYLE, OF NEW ORLEANS, LOUISIANA.

STRAINER FOR WASTE-HOLES.

SPECIFICATION forming part of Letters Patent No. 769,152, dated September 6, 1904.

Application filed January 21, 1904. Serial No. 189,988. (No model.)

To all whom it may concern:

Be it known that I, JOHN HENRY DOYLE, a citizen of the United States, and a resident of New Orleans, in the parish of Orleans and State of Louisiana, have invented certain new and useful Improvements in Strainers for Waste-Holes, of which the following is a specification.

My invention relates to strainers for waste-holes, more particularly to strainers for waste-holes of sinks, tubs, and basins in which a flushing-pipe is employed and runs from the supply-pipe into the waste-hole and drain-pipe.

15 It has for its object to provide a strainer for waste-holes comprising a perforated plate adapted to cover the waste-hole and a solid plate adapted to cover the flushing-pipe.

20 It has for a further object to provide a device of the character set forth embodying advantages in point of usefulness, simplicity, inexpensiveness, and general utility.

25 In the drawings, Figure 1 is a vertical sectional view of a basin, showing my device applied therein. Fig. 2 is a sectional view taken on the line *y y* of Fig. 1. Fig. 3 is a perspective view of my device.

Corresponding parts in all the figures are denoted by the same reference characters.

30 Referring to the drawings, 1 designates the basin, having a waste-hole 2, leading into a waste-pipe 3, provided with a gooseneck-trap 4, the construction so far described being old and well known. The sink is provided with 35 a groove 5 in its back wall and bottom, in which is seated the flushing-pipe 6, leading from the supply-pipe 7 and into the waste-opening and drain-pipe, this construction, with the exception of the groove provided in 40 the walls of the basin, being the same as shown in a patent issued to me, this groove being for the purpose of sinking the flushing-pipe out of the way. For the purpose of covering over this pipe and holding it in place and 45 also for forming a strainer for the waste-pipe I provide a device comprising a cup-shaped plate 8, having perforations 9 in its

bottom 10, registering with the waste-hole; a flange 11, provided with holes 12, through which screws 13 are inserted and into the 50 basin to fix it in place, and an upwardly-projecting plate 13^a, adapted to cover the groove in which the flushing-pipe is seated, which is secured in place by screws 14, inserted through holes 15 and into the basin. It will be understood that the upwardly-extending plate is to be bent or formed so as to correspond to the 55 contour of the interior of the receptacle in which the device is applied.

The device is applied as follows: The flushing-pipe is forced into the groove in the basin, sink, or other receptacle. The cupped part of the plate 8 is inserted into the waste-hole thereof, and the plate 13^a placed over the groove in which the flushing-pipe is seated, 65 and the device is then secured to the sink by means of the screws 13 and 14.

Having thus described my invention, I claim and desire to secure by Letters Patent—

1. The combination with a receptacle of the 70 character described having a waste-hole, and a flushing-pipe leading into said hole, of a strainer comprising a plate having perforations registering with said hole and a plate projecting therefrom and covering the flush- 75 ing-pipe, substantially as described.

2. The combination with a receptacle of the character described having a waste-hole, a groove extending from the top of the receptacle into the waste-hole and a flushing-pipe 80 seated in said groove and extending into the waste-hole, of a strainer having perforations registering with said hole and a plate projecting therefrom and covering said groove and flushing-pipe, substantially as described. 85

3. The combination with a receptacle of the character described having a waste-hole and a flushing-pipe leading into said hole, of a strainer comprising a cup-shaped plate seated in said hole and having perforations in its 90 bottom and a plate projecting therefrom and covering said pipe, substantially as described.

4. The combination with a receptacle of the character described having a waste-hole, a

groove leading from the top of the receptacle into said hole and a waste-pipe seated in said grooves, of a cup-shaped strainer comprising a plate seated in said hole and having perforations in its bottom and a plate projecting therefrom and covering said groove and pipe therein, substantially as described.

In testimony whereof I have signed my name in the presence of the subscribing witnesses.

JOHN HENRY DOYLE.

Witnesses:

HY REINHARDT,
JNO. R. McMAHON.
